UNITED STATES PATENT OFFICE

2,246,187

WASHING MACHINE

Gosta E. Olsson, Bridgeport, Conn., assignor to
 General Electric Company, a corporation of
 New York

Application November 17, 1938, Serial No. 241,013

9 Claims. (CL. 68—133)

The present invention relates to washing machines of the type having an agitator for effecting washing.

The object of my invention is to provide an improved construction and arrangement in washing machines of this type, and in particular to provide an improved control for the agitator.

For a consideration of what I believe to be novel and my invention, attention is directed to the following description and the claims appended thereto.

In the accompanying drawing, Fig. 1 is a sectional elevation of a washing machine embodying my invention; Fig. 2 is a sectional view of the upper end of the agitator; Fig. 3 is a sectional view taken on line 3—3 of Fig. 2; and Fig. 4 is a sectional view taken on line 4—4 of Fig. 2.

Referring to the drawing, there is shown a washing machine having a sheet metal tub 1 seated on a rubber bead 2 on the upper edge of a skirt 3 having supporting legs 4. Extending diametrically across the skirt and fixed at either end thereto is a gear case 5 containing the driving mechanism for the washing machine, which is driven by an electric motor 6 mounted on the gear case. At one end of the gear case is a wringer post 7 which extends upward along the outside of the tub. On the upper end of the wringer post (not shown) the usual wringer may be mounted. The wringer is driven by a continuously rotating shaft (not shown) extending from the gear case up through the wringer post. At the center of the tub is a tubular post 8 fixed at its lower end to the gear case and projecting upward through a central opening in the bottom of the tub. The bottom of the tub is clamped between a flange 9 on the post 8 and a nut 10 threaded on the post. Suitable sealing washers 10' are arranged between the upper and lower surfaces of the tub and the adjacent surfaces of the flange 9 and the nut 10. Extending from the gear case up through the post 8 is a shaft 11 which is continuously oscillated by the driving mechanism within the gear case. Mechanism for oscillating the shaft 11 and for rotating the shaft extending through the wringer post 7 is well known in the art, and illustration thereof is not required for the purposes of the present invention. The shaft 11 is journaled in a sleeve bearing 12 fixed in the upper end of the post 8. The upper end of the post 8 is located above the normal water level in the tub so that there is no danger of leakage around the shaft 11.

On the tubular post 8 is mounted a bladed agitator 13 having a hub 14 at its upper end

journaled on a driving head 15 pinned to the shaft 11 and having a tubular body portion depending therefrom around the post 8. The agitator is guided on the lower end of the post by a collar 16 fixed in the agitator which bears on a bearing 17 fixed on the outside of the post. The agitator is supported by a thrust washer 18 resting on the upper end of the agitator post 8 and engaging a shoulder 19 on the under side of the agitator hub. The agitator hub is slidable on the driving head 15 so that the agitator may be lifted off the shaft for cleaning.

Slidably carried in radial slots 20 in the driving head 15 are diametrically opposite clutch keys 21 having pointed teeth 22 on their outer edges engageable with complementary axially extending grooves 23 in the agitator hub 14. The keys 21 are held in the inner position as shown in Fig. 4 by a resilient split ring 24 fitting in a circumferential groove 25 in the driving head and in notches 26 in the clutch keys. In the inner position the ends of the teeth 22 are within the periphery of the driving head 15 so that the agitator is not oscillated by the shaft 11. The lower edges of the keys 21 rest on shoulders 27 (Fig. 2) at the bottom of the slots 20. Upward movement of the keys in the slots 20 is prevented by a plate 28 fixed to the upper end of the driving head. In the center of the driving head 15 is an axially extending bore 29 slidably receiving the enlarged lower end 30 of a plunger 31. The plunger is reciprocated by a cap 32 having walls 33 depending around the agitator hub and having a flange 34 at the center rotatable on a reduced portion 35 of the plunger and held between a shoulder 36 on the plunger and a screw 37 threaded therein. The cap 32 covers the upper end of the agitator hub and keeps water splashed over the upper end of the agitator from leaking around the shaft. The plunger is held on the agitator by a plate 38 fixed on the agitator hub by having its edges 39 spun into a groove 40. The body of the plunger is slidable in an opening 41 at the center of the plate 38. With this arrangement the plunger can have a reciprocating movement in the bore 29 limited by the engagement of the plate 38 with a shoulder 42 on the plunger and with the flange 34 on the cap 32.

50 The plunger is provided with a tapered end 43 which cooperates with tapered surfaces 44 on the clutch keys to move the keys radially outward upon downward movement of the plunger. Upon upward movement of the plunger the keys are moved inward by the split ring 24. In the outer

position the pointed teeth 22 of the clutch keys engage the complementary grooves 23 in the agitator hub and complete a driving connection from the continuously oscillating shaft 11 to the agitator. The angle of the cam surfaces 44 and of the pointed end 43 of the plunger is such that the driving forces cannot cause an upward movement of the plunger. These angles are illustrated as approximately 45°. Due to the pointed ends of the clutch keys and the tapered sides of the grooves 23, there is no lost motion between the clutch keys and the agitator hub.

During the oscillation of the agitator there is a tendency for the agitator to move upward off the agitator shaft. This is prevented by a snap ring 45 carried in a circumferential groove 46 in the teeth 47 between the grooves 23 of the agitator hub. The snap ring 45 is engaged by the notches 26 in the clutch keys and thereby prevents axial movement of the agitator hub with respect to the agitator shaft. From one aspect the snap ring 45 and the notches 26 serve as a detent for preventing movement of the agitator off its driving shaft.

When the agitator is not operating, the cap 32 is in the upper position shown in Fig. 2 and the clutch keys 21 are maintained in the inner position by the split ring 24. Under this condition the agitator remains stationary during the continuous oscillation of the shaft 11. To effect operation of the agitator, the cap 32 is pushed downward, causing the plunger 31 to be moved downward and the cam surfaces on the pointed end 43 thereof to engage the cam surfaces 44 on the clutch keys and force the clutch keys outward into engagement with the grooves 23 in the agitator hub. Since the cap is freely rotatable on the plunger 31, it can be comfortably gripped by the operator. The outward movement of the clutch keys is facilitated by the fact that the teeth 47 are pointed. It is therefore impossible for the pointed ends 22 of the clutch teeth to jam against the ends of the teeth 47. The outward movement of the clutch teeth establishes a driving connection from the agitator shaft 11 to the agitator. In the driving position the notches 26 in the clutch teeth engage the snap ring 45 and prevent upward movement of the agitator. The driving connection to the agitator is released by lifting the cap 32, returning the plunger 31 to the position shown in Fig. 2. The clutch keys are then returned to the inner position by the split ring 24. The tapered side walls of the grooves 23 cooperate with the tapered ends of the teeth 22 to assist in forcing the clutch keys to the inner position. While the clutch keys are in the inner position the agitator may be lifted out of the tub for cleaning.

What I claim as new and desire to secure by Letters Patent of the United States, is:

1. In a washer, a vertical shaft, an agitator having a hub rotatable relative to the shaft, said hub being slidable relative to the shaft whereby the agitator may be lifted off the shaft, a clutch member carried by the shaft movable into and out of engagement with the hub to make and break a driving connection from the shaft to the agitator, and normally separated interengaging parts on the hub and clutch member engageable in the driving position of the clutch member to prevent axial movement of the agitator off the shaft during its operation.

2. In a washer, in combination with a power shaft and an agitator having a hub rotatably surrounding the shaft, said hub being slidable

relative to the shaft whereby the agitator may be lifted off the shaft, grooves in said hub, radially movable clutch keys in said shaft, means for moving said clutch keys radially into and out of engagement with said grooves to make and break a driving connection between the shaft and the agitator, and detent means preventing lifting of the agitator off the shaft comprising normally disengaged parts on the hub and at least one of the clutch keys engageable by movement of the clutch keys to the driving position.

3. In a washer, a vertical shaft, an agitator having a hub rotatable relative to the shaft, said hub being slidable relative to the shaft whereby the agitator may be lifted off the shaft, axially extending grooves in the hub, a circumferential groove in the portions of the hub between said axial grooves, a snap ring in the circumferential groove, clutch keys in the shaft movable into and out of engagement with said axial grooves to make and break a driving connection to the agitator, and notches in said keys engageable with the snap ring when in the driving position for holding the agitator against movement off the shaft.

4. In a washer, in combination with a power shaft and an agitator having a hub rotatably surrounding the shaft, said hub being slidable relative to the shaft whereby the agitator may be lifted off the shaft, axially extending grooves in the hub having tapered side walls, clutch keys in the shaft having tapered portions movable into and out of engagement with the tapered side walls of the grooves, means for moving the clutch keys, and detent means preventing lifting of the agitator off the shaft comprising normally disengaged parts on the hub and at least one of the clutch keys engageable by movement of the clutch keys to the driving position.

5. In a washer, in combination with a power shaft and an agitator having a hub surrounding the shaft, said hub being slidable relative to the shaft whereby the agitator may be lifted off the shaft, pointed teeth in the hub having the ends thereof bearing on the shaft and defining axially extending grooves in the hub, clutch keys in the shaft having pointed ends movable into and out of said grooves to make and break a driving connection to the agitator, means for moving the clutch keys, and detent means preventing lifting of the agitator off the shaft comprising normally disengaged parts on the hub and at least one of the clutch keys engageable by movement of the clutch keys to the driving position.

6. In a washer, a vertical shaft, an agitator having a hub rotatable relative to the shaft, said hub being slidable relative to the shaft whereby the agitator may be lifted off the shaft, radially movable clutch members for making and breaking a driving connection between the agitator and shaft, and detent means cooperating with the clutch members in the driving position for preventing axial movement of the agitator off the shaft.

7. In a washer, in combination with a power shaft and an agitator having a hub rotatably surrounding the shaft, said hub being slidable relative to the shaft whereby the agitator may be lifted off the shaft, radially movable clutch keys in the shaft movable into and out of engagement with said hub to make and break a driving connection between the shaft and the agitator, a plunger in the shaft having a tapered end, cam surfaces on the clutch keys cooperating with said

tapered end whereby downward movement of the plunger forces the keys radially outward into engagement with the hub, and detent means preventing lifting of the agitator off the shaft comprising normally disengaged parts on the hub and at least one of the clutch keys engageable by movement of the clutch keys to the driving position.

8. In a washer, a vertical shaft, an agitator having a hub rotatable relative to the shaft, said hub being slidably relative to the shaft whereby the agitator may be lifted off the shaft, axially extending grooves in the hub, detent means in said grooves, clutch keys in the shaft movable into and out of engagement with said grooves to make and break a driving connection to the agitator, and notches in said keys engageable with said detent means when in the driving

position for holding the agitator against movement off the shaft.

9. In a washer, in combination with a power shaft and an agitator having a hub rotatably surrounding the shaft, radially movable clutch keys in the shaft movable into and out of engagement with said hub to make and break a driving connection between the shaft and the agitator, tension means encircling the clutch keys and fitting in notches in the keys and in grooves in the shaft for holding the keys in the inner position, a plunger in the shaft having a tapered end, and cam surfaces on the clutch keys cooperating with said tapered end whereby downward movement of the plunger forces the keys radially outward into engagement with the hub.
